NURSERY TRAY

Ted L. Paxton, P.O. Box 2006, Magnolia Center Station,
Riverside, Calif. 92506

Filed Sept. 1, 1966, Ser. No. 3,678

Term of patent 14 years

(Cl. D58—13)

FIG. 1

FIG. 2

FIG. 1 is a top perspective view of a nursery tray showing my new design.

FIG. 2 is an end elevational view thereof.

The side and end opposite those shown in the foreground in FIGURE 1 are identical thereto while the downward facing hidden surface of the bottom is merely the converse of the upwardly disposed visible surface thereof.

I claim:

The ornamental design for a nursery tray, as shown and described.
